UNITED STATES PATENT OFFICE.

CHARLES E. WILSON, OF HOOD RIVER, OREGON

ELECTRIC SMELTING FURNACE.

No. 921,325.

Patented May 11, 1909.

Application filed July 30, 1908. Serial No. 446,052.

To all whom it may concern:

Be it known that I, CHARLES E. WILSON, a citizen of the United States, residing at Hood River, county of Hood River, and State of Oregon, have invented a certain new and useful Improvement in Electric Smelting-Furnaces, of which the following is a specification.

My invention relates to a new and useful improvement in electric smelting furnaces generally and more particularly to such furnaces as are used for the production of ferro titanium in steel foundries, and has for its object to provide an exceedingly simple and effective device of this character in which the air would be prevented from entering the crucible.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by letter to the accompanying drawing forming a part of this specification, in which the figure in the drawing is a view partly in section and partly in elevation.

In carrying out my invention I provide a melting receptacle or crucible A which may be of any desired shape or size which is built of chrome bricks B and carbon C, and around these is placed a metallic plate D. The sides of the crucible are built on an angle so that the lower portion of said crucible is smaller than the upper, and leading from the lower portion thereof is an opening E about the outer end of which is placed a chute F leading to the ladle G.

On top of the crucible is placed a suitable water cooled jacket H through which are formed suitable openings I to allow the electrodes to pass in the crucible A as will be hereinafter described. Through one edge is formed another hole J in which is fitted the valve K against which rests the valve L. Between the openings I is formed another opening M into which leads the screw conveyer N above which is secured a hopper O into which may be placed the material which the conveyer is to carry into the crucible A.

P indicates tubes bolted to the water cooled jacket above the openings I and formed with

the upper ends are the flanges Q and about these tubes P are placed the tubes R having inwardly extending flanges S which engage with the flanges Q formed on the tubes P. These flanges S are adapted to fit over close against the outside of the tubes P so as to prevent any air from entering said tubes and insulating material P' is placed between the tubes P and the jacket H in order to prevent the short circuiting of the current. The electrodes T are adapted to pass through these tubes into the crucible A and are held securely to the upper tube R by the ring U which is clamped around the electrodes and secured together by the bolts U'. On the lower part of these rings are formed flanges V by means of which they may be clamped to the tube R by the bolts V'. Formed with or secured to the rings U are the eyes W to which are secured the chains W', said chains being carried by the movable carriage Y.

A' represents an open hearth furnace in which the steel is prepared before entering the crucible A of the electric furnace and leading from this open hearth furnace is a chute B' the outer end of which is in proximity to the valve L so that when said valve is raised the steel will be allowed to run through the opening J into the crucible A.

In practice the mixture is crushed until it is about like coarse sand well mixed and heated to a red heat then it is placed in the hopper O and by turning the screw conveyer N it will carry the mixture into the crucible A. The electric current is then turned on to the electrodes T which will at once reduce the mixture and should the gases from the reduction of ores accumulate in the crucible until the pressure is raised sufficient to lift the valve and allow the gases to escape when a sufficient amount of titanium has been reduced the valve F is opened and the steel allowed to run from the open hearth furnace A' to the crucible A at which time it will mix with titanium or any other alloy which might be placed in the crucible. When the steel has had time to thoroughly mix with or take up the titanium it is tapped into the ladle G and carried to the foundry. It is advisable to feed the mixture into the furnace very slowly so that no great variation in the temperature will be caused.

The reason for heating the charge before placing it in the crucible is to avoid explosions the temperature being so high that the least bit of dampness will cause explosion which would wreck the furnace.

Of course I do not wish to be limited to the exact details of construction as these may be varied without departing from the spirit of my invention.

Having thus fully described my invention, what I claim as new and useful, is—

1. In a device of the character described, a melting receptacle or crucible the inner walls of which slant inward toward the bottom, a water cooled jacket having suitable openings formed therein placed on top of said melting receptacle or crucible, a screw conveyer leading to one of the openings, a hopper secured above said screw conveyer in which the mixture is adapted to be placed, a valve placed over one of said openings, tubes placed over a number of the openings, a second set of tubes slightly larger than the first named tubes and adapted to slide up and down on the outside of the first named tubes, electrodes passing through said tubes into the receptacle or crucible, and means for raising or lowering said electrodes or removing them altogether, as and for the purpose set forth.

2. In a device of the character described, a melting receptacle or crucible the inner walls of which slant inward toward the bottom, a water cooled jacket having suitable openings formed therein placed on top of said melting receptacle or crucible, a screw conveyer leading to one of the openings, a hopper secured above said screw conveyer in which the mixture is adapted to be placed, a valve placed over one of said openings, tubes placed over a number of the openings, a second set of tubes slightly larger than the first named tubes and adapted to slide up and down on the outside of the first named tubes, electrodes adapted to pass through the tubes into the receptacle or crucible, rings adapted to be clamped about the upper end of said electrodes, means for clamping said rings to the upper tube, and means for moving the upper tube up and down, as and for the purpose set forth.

3. In a device of the character described, a melting receptacle or crucible the inner walls of which slant inward toward the bottom, a water cooled jacket having suitable openings formed therein placed on top of said melting receptacle or crucible, a screw conveyer leading to one of the openings, a

hopper secured above said screw conveyer in which the mixture is adapted to be placed, a valve placed over one of said openings, tubes placed over a number of the openings, a second set of tubes slightly larger than the first named tubes and adapted to slide up and down on the outside of the first named tubes, electrodes adapted to pass through the tubes into the receptacle or crucible, rings adapted to be clamped about the upper end of said electrodes, means for clamping said rings to the upper tube, eyes formed with or secured to the rings, a movable carriage, chains secured to said movable carriage and to the eyes formed with or secured to the rings so that the electrodes may be moved up and down or entirely removed from the receptacle or crucible, and means for supplying the receptacle or crucible with steel, as shown and described.

4. In a device of the character described, a melting receptacle or crucible the inner walls of which slant inward toward the bottom, a water cooled jacket having suitable openings formed therein placed on top of said melting receptacle or crucible, a screw conveyer leading to one of the openings, a hopper secured above said screw conveyer in which the mixture is adapted to be placed, a valve placed over one of said openings, tubes placed over a number of the openings, a second set of tubes slightly larger than the first named tubes and adapted to slide up and down on the outside of the first named tubes, electrodes adapted to pass through the tubes into the receptacle or crucible, rings adapted to be clamped about the upper end of said electrodes, means for clamping said rings to the upper tube, eyes formed with or secured to the rings, a movable carriage, chains secured to said movable carriage and to the eyes formed with or secured to the rings so that the electrodes may be moved up and down or entirely removed from the receptacle or crucible, an open hearth furnace placed above the crucible or receptacle at one side thereof, and a chute leading from the open hearth furnace to the valve for conveying the steel from the open hearth furnace to the receptacle or crucible, as shown and described.

In testimony whereof, I have hereunto affixed my signature in the presence of two subscribing witnesses.

CHARLES E. WILSON.
